UNITED STATES PATENT OFFICE.

JOHN ZANDER, OF CHICAGO, ILLINOIS.

DISTILLATION APPARATUS.

Application filed July 21, 1920. Serial No. 398,010.

To all whom it may concern:

Be it known that I, JOHN ZANDER, a citizen of the United States, residing at Chicago, in the county of Cook and State of Illinois, have invented a new and useful Improvement in Distillation Apparatus, of which the following is a specification.

My invention relates, more particularly, though not exclusively, to the art of extracting oils from oil-bearing shale-like material which is commonly found in natural condition in which the oil is usually in the form of bitumen impregnating the solids.

My primary object is to provide for the economical extraction of the oils from oil-bearing solids, and the obtaining therefrom of a relatively large proportion of the contained oils; and to provide a novel, simple and economical construction of apparatus by which the oil-extracting operation may be carried on as a continuous process and at the minimum expense.

Referring to the accompanying drawings wherein I have shown a desirable construction of apparatus for the practicing of my improved method and one which constitutes a desirable embodiment of my improvements in still constructions:—

Figure 1 is a view in sectional elevation, the section being taken longitudinally of the still construction, the portion of the structure in the upper part of the view being a continuation of the structure in the lower part of the view, these two portions of the structures being thus shown to more clearly bring out the details of the end portions of the still. Figure 2 is a plan view of the part of the structure shown in Fig. 1. Figure 3 is a section taken at the line 3—3 on Fig. 1 and viewed in the direction of the arrows. Figure 4 is an end view of the structure showing it as viewed from the right in Fig. 1; and Figures 5 and 6, sections taken at the lines 5 and 6 on Fig. 3 and viewed in the direction of the arrows.

The particular construction illustrated is formed of a furnace preferably horizontally disposed and generally illustrated at 10, the walls of which are made of any desirable fire-resisting material and its interior construction preferably being such, as hereinafter described, as to cause the products of combustion to travel through the furnace in a tortuous path. The furnace is shown as adapted for the burning of gas introduced into the furnace chamber through a burner

represented at 11 extending into an inlet 12 in an end-wall 13 of the furnace structure, this burner being supplied with gas from any suitable source, but preferably with gas evolved from the material treated in the still, as hereinafter explained, the furnace 10 being provided at the end thereof opposite that at which the burner 11 is located, with an outlet stack represented at 14.

The structure providing the chamber or compartment in which the material to be operated on, is subjected to the desired heat, is represented generally at 15, this structure in accordance with the structure shown being preferably formed of metal and involving a shell 16 which is located in, and extends longitudinally through, the furnace structure 10, in which position it is subjected to the heat of the furnace.

The shell 16 is shown as of rectangular shape in cross-section, the end thereof adjacent the stack 14 (the left hand end in Fig. 1, lower view) being closed and its opposite end at which it extends through the furnace wall 13, being open. The shell 16 is provided with a substantially horizontally-disposed partition member 17 which extends lengthwise of the shell, but short of the end of the latter adjacent the stack 14, this partition, which extends the full width of the shell 16 being formed, as to the portion thereof which is located within the shell, with an air space 18.

The bottom of the furnace structure 10 is continued to the right in Fig. 1 beyond the end wall 13, and rising therefrom are the walls 100 and 101 shown as spaced apart the same distance as the vertical side walls of the shell. The top and bottom walls of the shell, and the partition 17, are continued outwardly beyond the wall 13 at which points they are deflected downwardly as represented at 19, 20 and 21, respectively. The extensions of the bottom wall of the shell 16 and the partition, as referred to, are also provided with upwardly deflected, or inclining, portions 22 and 23, respectively, forming continuations of the deflected portions 20 and 21, respectively, whereby these extensions are of trough-like form in cross-section as represented. The extensions of the top and bottom walls and the partition of the shell, and just described, are preferably of a width equal to the width of the space between the walls 100 and 101 into the space between which they extend

and are suitably joined thereto to produce water-tight joints, the extension portion 22 preferably containing an opening 24, shown as above the lower edge of the extension 19, for permitting the liquid-seal material, hereinafter referred to, to flow into the trough formed of the plate portions 21 and 22.

As a preface to the following description, it may be stated that in the operation of the structure the oil-bearing material to be subjected to heat, is introduced into the shell 16 of the still at the right hand end in the upper view of Fig. 1 between the plate portions 19 and 20 and moved along the partition 17 from which it discharges upon the bottom of the shell and is thence moved along the latter to the right in Fig. 1 to the outlet for the material. It is preferred that the furnace be so constructed that the greatest heat to which the material is subjected, be applied to the material adjacent the discharge end therefor of the furnace, and that the lowest heat to which it is subjected be applied at the material-inlet end of the furnace. As a means for accomplishing this result I have shown the furnace structure as provided with a series of tortuous passages through which the products of combustion pass in their travel to the stack. The furnace structure shown is provided toward one end and below the shell 16, with a pier, or partition, 25 which is spaced at its lateral edges from substantially vertically disposed partitions 26 and 27 which extend lengthwise through the furnace chamber and divide it into a central chamber 28 into which the burner 11 discharges, and the side chambers or flues 29 and 29^a which are located laterally beyond the side-walls of the shell 16. The partitions 26 and 27 beyond the pier 25 are formed with laterally and inwardly-projecting wall sections 30 and 31, respectively, which reach short of each other substantially midway of these partitions and form a restricted channel 32, the bottom wall of the furnace structure 10, at the end thereof adjacent the stack 14 and beyond the extensions 30 and 31, containing recesses 33 and 34 which extend under the partitions 26 and 27 and communicate with the flue passages 29 and 29^a, the metal plates forming the side-walls of the shell 16 being extended upwardly beyond the top wall of the shell 16 represented at 35, as clearly shown in Fig. 5, throughout the length of the furnace chamber thereby affording a flue 36 which is in communication, adjacent the end of the structure into which the material to be operated on, is introduced, with the flue passages 29 and 29^a, through the medium of recesses 37 and 38 formed in the lower surface of the top wall of the furnace structure 10. It will be understood

from the foregoing that the products of combustion are caused to take a course as illustrated by the arrows in the drawings, the products of combustion, referring to Fig. 3, passing from the burner into the chamber 28 around the pier 25, thence through the opening 32, and downwardly and laterally through the recesses 33 and 34 into the flue passages 29 and 29^a adjacent the stack-end of the furnace structure; thence backwardly alongside the side walls of the shell 16 and outwardly and inwardly through the recesses 37 and 38 into the flue passage 36 and thence to the left in Fig. 1 to the stack 14 from which they discharge.

The degree of heat to which the oil-bearing material is to be subjected may depend somewhat upon the character of the material, but by way of example it may be stated that in the treating of oil-bearing shale it will be desirable to heat the material adjacent the point at which it enters the shell, to about 250° F., and graduate the heat along the course through which the material passes in the shell to about 900 or 1000° F. adjacent the end of the furnace at which the material is withdrawn therefrom.

In the arrangement shown provision is made for feeding the material to be operated on, into the shell and moving it therethrough in the course hereinbefore referred to, along the upper surface of the partition 17 and the bottom wall of the shell, these means, as shown, comprising an endless flexible element represented at 39 which may be in the form of a pair of endless chains as shown, parallel, spaced apart and extending at one end of the furnace structure over sprockets 40 secured to, and spaced apart on, a shaft 41 journaled in brackets 42 on the furnace structure, this shaft being driven as through the medium of the gears 42^a and 43, the latter being fixed on a shaft 44 suitably journaled in bearings 45 on the furnace structure and driven as through the medium of the drive 46 of any suitable construction operated from the belt-driven pulley 47. The chains referred to extend at the other end of the furnace over a pair of sprockets 48 located in the shell 16 and secured to a shaft 49 journaled in any suitable way. The sprockets 40 and 48 are so arranged that the upper portions of the chains extend slightly above the upper surface of the partition 17 and its extensions 20 and 22 and the lower portions of these chains extend slightly above the bottom wall of the shell 16 and the extensions 21 and 23 thereof, there being provided above the said extensions of the partition and bottom wall of the shell, pairs of sprockets 50 and 51 fixed on shafts 52 and 53, respectively; the sprockets 50 and 51 engaging the chains and being so positioned as to cause the chains to

be deflected adjacent the extensions of the partition and bottom wall of the shell, to travel in a path parallel with these extended trough-like portions, as shown. The endless element 39, formed of the chains as stated, further comprises a series of blades or pushers 54 secured at their opposite ends to the chains referred to and extending preferably at right angles to the path of movement of the chains, the entire arrangement described being such that the blades 54 in the movement of the chains are caused to move in contact with, and along, the upper surfaces of the partition and its trough-like extension and the upper surface of the bottom wall of the shell and the trough-like extension of the latter.

The outlet in the shell 16, for the vapors and gases evolved in the heating of the material as hereinbefore explained, is represented at 55, this outlet being connected with a pipe 56 which opens into a condenser coil 57 located in a cooling tank 58 supplied with cooling water as through the medium of a pipe 59 which may lead to any suitable source of supply, the other end of the cooling coil 57 being connected with a coupling 60 connected at its lower end with a goose-neck pipe 61 shown as extending into a position to discharge the liquid flowing from this pipe as hereinafter described, into a receptacle, such as the barrel represented at 62. The other end of the coupling 60 connects with a pipe 63 which has a depending extension 64 opening into a chamber 65 located in the cooling tank 58 and having communication therewith, as through the medium of the openings 66 in the tank 65, whereby water is supplied to this chamber, as for example to the level indicated in Fig. 4, the lower end of the pipe 64 extending into the water as shown for a purpose hereinafter explained.

The pipe 63 also connects with a pipe 67 valved, as indicated at 68, and opening into a pipe 69 connected with the burner 11 for supplying gas, as fuel, to the burner, the pipe 69 being shown as extending beyond the pipe 67 and equipped with a valve 70 for connection with any other suitable supply of gas to be used if desired.

In the operation of the structure any suitable liquid, preferably water, is introduced into the trough-like extensions of the partition 17 and the bottom wall of the shell 16, the water in the lower trough to extend above the under surface of the upper trough, and the water in the upper trough to extend above the lower extremity of the plate extension 19, the water preferably extending to the levels as noted in the drawing at 71 and 72, respectively, the opening 24 forming means whereby the water overflows from the upper trough into the lower trough.

The material from which the oil is to be removed, and which in the case of so-called oil-bearing shales is preferably preliminarily crushed into pieces about the size of a hazelnut, is introduced into the upper trough of which the plate sections 20 and 22 form the bottom, the material thus becoming immersed in the water bath. Assuming the furnace to be heated, as through the burner 11 as hereinbefore described, and the shaft 40 rotated in the direction of the arrow in Fig. 1 to actuate the blade-equipped endless element hereinbefore described, the blades 54 in moving along the upper surface of the upper trough, operate to engage the material in the trough and move it therefrom and along the upper surface of the partition 17 from which it discharges upon the bottom wall of the shell 16 where it is again engaged by the blades 54 and, by the latter moved to, and into, the lower trough, wherein it becomes immersed in the water in this trough, the blades in their continuing movement discharging the material at the right-hand end of the trough in Fig. 1 from which it may be conducted away in any desirable manner.

It will be noted that in so operating on the material there is caused to be presented in the shell water-vapor to an amount sufficient to cause the bitumen in the shale, under the action of the heat to which the material is subjected, to give up a large amount of the oils obtainable therefrom.

In the subjection of the solids to heat as stated, the volatile matter evolved therefrom passes out of the shell at its outlet 56, thence passing into the condenser coil 57 wherein the condensable vapors are condensed and discharged through the goose-neck 61 into a receptacle 62. The non-condensable gases derived from the material treated rise in the pipe 63, and pass into the pipe 67, and thence pass to the burner 11. The pipe 64 co-operating with the water-bath in the tank 65 which latter has an outlet 66, is provided as a relief for the pressure evolved in the shell 16 in the event that it approaches a degree which might blow out the liquid-seal at the inlet or outlet end of the shell, the pressure maintained in the shell being dependent upon the depth of the seal provided in the chamber 65. The gas which, in the event of excessive pressure, escapes from the pipe 64 discharges through the pipe 66 to storage or any desirable use. It may be found desirable to provide, instead of a single outlet for the vapors evolved in the shell, a plurality of such outlets arranged along the shell at different points, with condensing apparatus for each as described of the outlet 55, to separately conduct away from the shell and separately condense the vapors evolved at different temperatures, instead of commingling them, such modification being within my invention.

A pipe 58* serves to conduct from the

chamber 58 to the upper liquid-seal trough, outflow from this chamber, to supply the troughs with water.

While I have illustrated and described a particular apparatus involving structural features within my invention, and forming a desirable apparatus for practicing my improved method, I do not wish to be understood as intending to limit my invention thereto, as the structure may be variously modified and altered without departing from the spirit of my invention, and other forms of apparatus may be used in carrying out my improved method.

What I claim as new and desire to secure by Letters Patent is:

1. A still of the character set forth, comprising a chamber having floor sections arranged one above the other in spaced relation with an opening from the upper floor to the floor below it, said furnace having a liquid-seal inlet toward the end of the upper floor opposite that containing

said opening, and a liquid-seal outlet toward the end of the lower floor opposite that adjacent said opening, means for heating the material, and means operating through said liquid-seals for moving the material from said inlet along said floor sections and through said outlet. 30

2. A still of the character set forth, comprising a chamber having floor sections arranged one above the other in spaced relation with an opening from the upper floor to the floor below it, said furnace having a liquid-seal inlet toward the end of the upper floor opposite that containing said opening, and a liquid-seal outlet toward the end of the lower floor opposite that adjacent said opening, means for heating the material, and endless means operating through said liquid-seals for moving the material from said inlet along said floor sections and through said outlet. 35 40

JOHN ZANDER.
